UNITED STATES PATENT OFFICE

2,458,141

CRUCIBLE HANDLING DEVICE

Frank D. Bromley, Portsmouth, R. I.

Application December 7, 1945, Serial No. 633,401

2 Claims. (CL. 22—82)

1

My invention as described herein, and illustrated in the accompanying drawings, consists of a device for handling crucibles or other like containers, an object of which is to provide a crucible carrier and manipulator adapted to eliminate danger in the handling thereof.

Another object of my invention is to provide a self-adjusting crucible carrier.

A further object of this invention is to provide a combined carrier and pouring device for liquid or other containers.

Another object of my invention is to provide a crucible handling device adapted for use in connection with containers of various sizes and shapes and whereby to secure the container to the carrier.

A primary object of my invention is the provision of means whereby highly heated crucibles, ladles, or acid carboys or other like containers, the contents of which are dangerous, can be carried in safety without danger of breakage and which can be tilted for pouring the contents without danger to life or limb of handlers or workers.

Other features and advantages will become more readily apparent from the following description and the accompanying illustrative drawings in which:

Figure 1 is a top plan view of my device,

Figure 2 is a side elevational view thereof,

Figure 3 is a sectional view taken on line 3—3 of Figure 1,

Figure 4 is a detail top plan view of one member of my device, and

Figure 5 is a detail longitudinal sectional view of a hinge arm.

While one embodiment of my invention is illustrated in the above referred to drawings, it is to be understood that they are merely for the purpose of illustration and the various changes in construction may be resorted to in the course of manufacture in order that the invention may be utilized to the best advantage according to circumstances which may arise, without in any way departing from the spirit and intention of my device, which is to be limited only in accordance with the appended claims. And while I have stated the primary field of utility of my invention it remains obvious that it may be employed in any other capacity wherein it may be found applicable.

In the accompanying drawings, and in the following specification, the same reference characters are used to designate the same parts and elements throughout and in which 10, refers to

2

my invention in its entirety and 11, indicates a base or seat for a crucible or other container 12, said seat being provided with an annular upstanding rim 13, for preventing the container from slipping from the seat.

Hinged at various points around the seat and to said rim 13, at 14, 15, 16 and 17, are a series of arms 18, 19, 20 and 21, the free ends 22, of each of which incline inwardly and outwardly at 23 and 24, the inner incline being somewhat shaped to conform to the wall 25, of the crucible 12, and the outer incline for automatic adjustment of a hoop or band 26, thereupon.

Attached to the opposite sides of the hoop 26, are handle members 29 and 30, the one 29, of which may be straight and the other terminating in a U shaped handle grip 31. Coiled upon the inner ends of the handles are springs 34 and 35, against the outer ends of which slidably collars 36 and 37, are adapted to seat. Pivotally connected to the opposite sides of these collars are the terminal ends of the arms 42 and 43, are hooks 44 and 45, which are adapted to engage over the upper edge 46, of the crucible 12. The arms 18 to 21, are of such length that their heads 47, 48, 49 and 50, project above the belly portion 51, of the crucible 12, or other member to be carried upon the device.

Projecting horizontally out from each of the heads 47 to 50, are the upper ends of vertical retainer arms 53, 54, etc., within which the hoop 26, passes when the arms 29 and 30, are lifted up. These arms 53 and 54 which may be somewhat resilient, will hold the tapered hoop secured against the sharp incline of the arms 18 to 21, and in case the device should accidentally overturn or be turned up, the hold back clamps 55 and 56, will prevent the member 12, from becoming detached from the carrier 10. The inclined or tapered wall 57, of hoop 26, acting upon the quick inclines of arms 18 to 21, will securely bind the crucible 12, in the carrier and prevent movement thereof and also in case of a cracking of wall 25, as frequently happens while being used, the parts of said wall can not spread to allow the contents of the crucible to escape with probably injury to the carriers of the device. Being carried by the handle 29, and the U-shaped hand grips 31, will prevent the device from toppling over.

It is to be noted that the hoop 26, does not come into contact at any point with the crucible and is therefore air cooled, thus avoiding carrying heat to the handles.

It is thought that persons skilled in the art to

which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention that which I claim as new and desire to procure by Letters Patent is:

1. A handling device for containers comprising a base for a container, arms hinged to the base for pivotal movement relative to the containers on said base, a hoop surrounding said arms for retaining said arms in a raised position against the container, handles carried by said hoop for raising the same, collars carried by said handles, hold back clamps pivoted on said collars for engaging the upper edge of the container on said base, and resilient means between said hoop and said collars for normally holding said collars outwardly from said hoop.

2. The combination of claim 1 wherein said arms include inclined outer surfaces, said hoop having a tapered inner periphery for bearing against the outer surfaces of said arms.

FRANK D. BROMLEY.
